UNITED STATES PATENT OFFICE.

WALTER LUTTRINGHAUS, OF MAYWOOD, ILLINOIS.

DESIGN FOR A BERLIN KETTLE.

55,480.

Specification for Design.

Patented June 15, 1920.

Application filed February 19, 1917. Serial No. 149,682. Term of patent 14 years.

To all whom it may concern:

Be it known that I, WALTER LUTTRINGHAUS, a citizen of the United States, residing at Maywood, in the county of Cook and State of Illinois, have invented a new, original, and ornamental Design for Berlin Kettles, of which the following is a specification, reference being had to the accompanying drawing, forming part thereof.

The figure is a perspective view of a Berlin kettle showing my new design.

I claim:

The ornamental design for a Berlin kettle as shown.

WALTER LUTTRINGHAUS.
